UNITED STATES PATENT OFFICE.

THEODORA WORMLEY ROGERS, OF COLUMBUS, OHIO.

FLESH-REDUCING GARMENT.

1,264,977.

Specification of Letters Patent.

Patented May 7, 1918.

Application filed May 25, 1914. Serial No. 840,885.

To all whom it may concern:

Be it known that I, THEODORA WORMLEY ROGERS, a citizen of the United States, residing at Columbus, in the county of Franklin and State of Ohio, have invented certain new and useful Improvements in Flesh-Reducing Garments, of which the following is a specification.

My invention relates to flesh reducing 10 garments of that class which are adapted for the reduction of the hips or thighs of the wearer and has particular relation to the improvement of the construction shown in my former application for patent, Serial 15 Number 829,565, filed April 4, 1914.

The objects of my present invention are to provide a combined corset and hip and thigh reducing garment of improved construction and arrangement of parts; to provide a substantially integral garment which will embody a corset or a desirable portion thereof and a bifurcated garment so constructed as to insure pressure on those parts of the body which it is desired to reduce, thereby causing a gradual circulatory absorption of the adipose tissues and a consequent reduction in the size of the parts to which the pressure is subjected; to so construct my improved garment as to admit of desirable adjustment and to produce other improvements, the details of which will be more fully pointed out hereinafter.

The preferred embodiment of my invention is shown in the accompanying drawings, in which similar characters of reference designate corresponding parts, and in which:

Figure 1 represents the figure of a woman wearing one of my improved garments and showing the front view thereof.

Fig. 2 is a similar view showing portions of the side and back of the garment as it appears when worn.

As indicated in the drawing, my improved 45 garment combines a suitable corset or portion of a corset 1, which forms the greater part of the upper portion of the garment, with a downwardly extending flesh reducing garment member or portion 2, the latter 50 being formed of yielding material, preferably of knit elastic and comprising hip and thigh embracing portions 3 and downwardly extending leg portions 4. At the rear of the garment, the corset member 1 is open throughout its length, this opening being continued into the reducing member 2 to

a point in the crotch of said reducing member. The sides of this opening are adapted to be adjustably drawn together by lacing tapes, such as are indicated at 5 or the edges 60 may be otherwise suitably connected or united by adjustable means. A similar opening is formed at the front of the garment, as indicated at 6, and the edges of this opening are likewise adapted to be ad- 65 justably connected by suitable lacing strings 7 or other known means. This front opening 6 is likewise carried downward through the upper portion of the front of the garment member 2 to the point of bifurcation. 70 In combining the members 1 and 2 of my improved garment, I preferably provide the opposite sides of the flesh reducing member 2 with upwardly extending portions 8 which, as shown, are fitted in correspond- 75 ingly shaped recesses of the corset body 1. These side extensions 8, together with the body of the member 2, insure a desirable covering of the hips of the wearer with the yielding material of which the reducing 80 member 2 is formed.

In the construction of the elastic reducing member 2, I insert in the front and rear of said garment member, on opposite sides of each of the vertical openings thereof, separately formed pieces of yielding material 9, this construction being similar to that set forth in my said former application.

It will be understood that the garment herein described may by a proper manipulation of the lacing tapes or other adjustable connections, be made to fit the body with the desired degree of closeness and that by this means a proper degree of pressure on the hips or thighs or both may be exerted by the material forming the reducing member to create a desirable absorption of the adipose tissues and a resultant decrease in the size of the portion of the body embraced. It will be observed that by the employment of the inserted members 9, those portions or sections of the reducing member which actually bear upon the hips and thighs are thus narrowed, thereby permitting the hip portions of the garment to be 100 drawn tightly at the proper points through a more perfect control of the elastic movement of the material. Furthermore, the employment of the sections 9 permits the insertion of sections of such sizes and forms 105 as to aid in the fitting of the garment to the body of the person for whom it is intended.

As is shown at 10 in dotted lines on both the garment members 1 and 2, the stay strips or "bones" of the corset are preferably continued downward and secured in connection with the material forming the reducing member, thereby giving said reducing member the supporting and stiffening benefit which is ordinarily imparted to the corset.

10 As will be observed the wearer of my improved garment will not only receive the benefit to be derived through the pressure of the reducing member, but will have combined with said reducing member the effective portion of a desirable form of corset, which combination will add to both the convenience and comfort of the wearer. It will also be understood that my improved garment is simple of construction and that owing to the provision of legs, it may be worn with comfort and without retarding the movements of the wearer.

15 What I claim is:

1. A garment comprising a combined corset and compressor, the corset being of non-elastic material, the compressor being attached to the lower edge of the corset and including an elastic portion which encircles the body at the hips to cause hip pressure, 25 a pair of elastic thigh embracing portions attached to the hip embracing portion whereby the latter is held in position, and means common to both the corset and com-

pressor for regulating the closeness of fit of the garment.

2. A garment comprising a combined corset and compressor, the corset being of non-elastic material, the compressor being attached to the lower edge of the corset and including an elastic portion which encircles 35 the body at the hips to cause hip pressure, a pair of elastic thigh embracing portions attached to the hip embracing portion whereby the latter is held in position, and means at the front and rear of the garment 40 and common to both the corset and compressor for regulating the closeness of fit of the garment.

3. A garment comprising a combined corset and compressor, said corset being of non-elastic material and being cut out at oppositely located points and at the sides 45 of the same from its lower portion toward the waist line, said compressor being attached to the lower edge of the corset and being of elastic material and comprising a portion which completely encircles the body and extends up into said cut-out portions, and a pair of tubular leg pieces at the bottom of said encircling portion.

50 In testimony whereof I affix my signature in presence of two witnesses.

THEODORA WORMLEY ROGERS.
